UNITED STATES PATENT OFFICE.

HARRY FEDER, OF NEW YORK, N. Y.

DESIGN FOR A BOW.

40,405.

Specification for Design. Patented Dec. 14, 1909.

Application filed June 23, 1909. Serial No. 503,967. Term of patent 7 years.

To all whom it may concern:

Be it known that I, HARRY FEDER, a citizen of the United States, residing at 532 Broadway, in the city and county of New York and State of New York, have invented a new, original, and ornamental Design for Bows, of which the following is a specification.

My new and original design for bows has particular reference to bows of that class employed in connection with the sweat bands of hats and caps which conduce to ornamentation at the union of the two ends of the sweat band. It also has reference to bows

of this character as employed in the ornamentation of badges, buckles and the like.

With reference to the accompanying drawing, the figure is a plan view of a bow, as employed in connection with the sweat lining of a hat or cap, showing my new design.

I claim:

The ornamental design for a bow, as shown.

HARRY FEDER.
